(57) **CLAIM**

We claim the ornamental design for a compact cigarette manufacturing machine, as shown and described.

DESCRIPTION

FIG. 1 is a front-top-left side perspective view of a first embodiment of a compact cigarette manufacturing machine; FIG. 2 is a front-top-right side perspective view thereof; FIG. 3 is a rear-top-right side perspective view thereof; FIG. 4 is a rear-top-left side perspective view thereof; FIG. 5 is a top plan view thereof; FIG. 6 is a bottom plan view thereof; FIG. 7 is a left side elevation view thereof; FIG. 8 is a right side elevation view thereof; FIG. 9 is a front elevation view thereof; and, FIG. 10 is a rear elevation view thereof.

In the Figures, the broken lines show portions of a compact cigarette manufacturing machine that form no part of the claimed design.
